UNITED STATES PATENT OFFICE.

CHARLES FURNESS HATELY, OF CHICAGO, ILLINOIS, ASSIGNOR TO NATIONAL SURFACE GUARD COMPANY, OF CHICAGO, ILLINOIS, A CORPORATION OF ILLINOIS.

CATTLE-GUARD.

1,294,659.

Specification of Letters Patent. Patented Feb. 18, 1919.

Application filed October 25, 1917. Serial No. 198,435.

To all whom it may concern:

Be it known that I, CHARLES FURNESS HATELY, a citizen of the United States, residing at Chicago, in the county of Cook 5 and State of Illinois, have invented certain new and useful Improvements in Cattle-Guards, of which the following is a specification.

This invention relates to cattle guards, 10 and has reference more particularly to cattle guards of the type that are made from sheet metal and are formed with integral teeth struck or stamped up from the body portion or portions of the guard. A cattle 15 guard of the general class and structural type to which the present invention belongs is illustrated in Letters Patent to Bolinger, No. 1,156,856, dated October 12, 1915; and the object of the invention is to improve the 20 utility and efficiency of sheet metal guards of the class shown in said patent, this object being attained principally by a novel construction of the tooth bars of the guard whereby a largely increased number of teeth 25 for a given surface area is secured, and whereby also said teeth are more effectively and efficiently arranged or disposed over the surface of the guard. To this end, a cattle 30 guard of my present invention comprises the various features and details of structure hereinafter described and more particularly defined in the appended claims.

In order that my invention may be readily understood and appreciated by those familiar with the art in which it belongs, I 35 have illustrated in the accompanying drawings one practical and workable embodiment thereof; and referring thereto—

Figure 1 is a top plan view of a cattle 40 guard of my invention shown as applied in use, a few only of the tooth bars being shown in full detail since they are all alike;

Fig. 2 is an enlarged fragmentary perspective view of one of the tooth bars;

Figs. 3 and 4 are sections on the corresponding lines of Fig. 1.

Referring to the drawings, 5 designates the ties and 6 the rails of a railway track to which the cattle guard is principally applied 50 in service. As herein shown the complete guard is made in a plurality of sections disposed side by side, each section comprising a series of four parallel tooth bars rigidly connected in spaced relation. As the sec-

tions are all alike, a description of one will suffice for all.

A designates as an entirety each of the tooth bars, the ends 7 of which are flat and are riveted to transverse angle bars 8, these latter resting upon the ties 5 and being secured to the latter as by spikes 9. The marginal portions of each bar are bent downwardly to form underlying ribs or flanges 10, and these latter fit into transverse kerfs 11 formed in underlying angle bars 12, of which one or more may be used depending upon the length of the guard, the angle bars 12 serving as connecting and spacing members and also preferably resting upon the ties 5. To lock the tooth bars A to the bars 12, the portions of the flanges 10 lying in the kerfs 11 are swaged laterally as indicated at 10' in Fig. 4 so as to form a lock. From the intermediate portion of the bar that lies between the flanges 10 there are struck up two rows of substantially vertical main teeth 13 and 14 of inverted V-shape, these teeth lying substantially in the vertical planes of the ribs or flanges 10.

The guard as thus far described is substantially the guard disclosed in the Letters Patent hereinabove referred to, with the exception that in the present instance the teeth 13 and 14 are of unequal heights, the teeth 13 being somewhat taller than the teeth 14, and with the further exception that the intermediate skeleton web portion is of arch form instead of flat, this latter feature, however, forming no part of the present invention. My present improvements have to do 90 with the structural form of the tooth bar itself, and consist of the features next to be described.

It will be noted that, as above mentioned, the teeth 14 are somewhat shorter than the 95 teeth 13. The purpose of this construction is two-fold. In the first place, I have found that the guard is more efficient where the different series of teeth thereon are of unequal heights, and, in the second place, by 100 making the teeth 14 shorter than the teeth 13, a greater width is obtainable in the limbs 15 of the zigzag skeleton structure that is created by the punching out of the main teeth 13 and 14, thereby rendering it feasible 105 to punch out of the limbs 15 upwardly projecting auxiliary teeth 16. These auxiliary teeth may be punched out of all of the limbs

15 if desired, but I have herein shown them as punched out of alternate limbs, which is sufficient for all practical purposes. These teeth 16 are somewhat lower than the teeth 5 14, and lie substantially midway between the main teeth 13 and 14. Out of the main teeth 13 are preferably struck a series of auxiliary teeth 17 that extend laterally of the teeth 13 on the outer side of the latter and preferably 10 have an upward and outward inclination of approximately 45°.

One result of the foregoing structure is 15 that the number of teeth in a given surface area of the guard is doubled as compared with the structure of the Bolinger patent above referred to, and consequently the spacing of the teeth throughout the surface of the guard is reduced by approximately one-half. This feature, together with the 20 feature of the unequal heights of the different series of teeth, renders the guard much more efficient not only for keeping horses and cattle off the railway track but also for preventing smaller hooved animals, such as 25 hogs and sheep, from crossing or trespassing on the railway track. Manifestly, the auxiliary teeth 17 serve to reduce the width of the open spaces between the bars, while the auxiliary teeth 16 similarly serve to reduce the 30 space between the marginal teeth 13 and 14 of each bar. The result is a guard, the surface area of which is so thickly studded with projecting points that it is impossible for any farm animals to walk upon or over it. 35 In a companion application filed concurrently herewith, Serial No. 198,434, I have disclosed and broadly claimed the feature of auxiliary teeth struck from and projecting laterally of the main teeth, and also the feature of an intermediate row of teeth carried 40 by the web member of the bar and lying between the two rows of main teeth. The present invention is a specific embodiment of the

broad invention disclosed and claimed in the said companion application. 45

I claim:

1. A cattle guard comprising a plurality of separated spaced bars, each formed with parallel vertical flanges and a connecting web, said flanges having on their upper edges 50 rows of upstanding teeth struck up from said web, the teeth of one row being higher than the teeth of the other row, and said web carrying a row of shorter teeth struck upwardly therefrom. 55

2. A cattle guard comprising a plurality of separated spaced bars, each formed with parallel vertical flanges and a connecting web, said flanges having on their upper edges 60 rows of upstanding teeth struck up from said web, the teeth of one row being higher than the teeth of the other row and formed with laterally projecting auxiliary teeth, and said web carrying a substantially central row of shorter teeth struck upwardly there- 65 from.

3. A cattle guard comprising a plurality of spaced bars, each formed with parallel vertical marginal flanges having on their upper edges marginal rows of teeth of unequal heights, and a struck up web extending intermediate of said marginal rows of teeth and provided with short teeth struck from 70 said web.

4. A cattle guard comprising a plurality 75 of spaced bars, each formed with parallel vertical marginal flanges having on their upper edges marginal rows of teeth of unequal heights and one of said rows of teeth being formed with laterally projecting auxiliary teeth, and a struck up web extending intermediate of said marginal rows of teeth and provided with short teeth struck up 80 from said web.

C. FURNESS HATELY,

Copies of this patent may be obtained for five cents each, by addressing the "Commissioner of Patents, Washington, D. C."
